LIPSTICK CONTAINER

Philip Courtney, New York, N. Y.

Application November 6, 1956, Serial No. 43,675

Term of patent 14 years

(Cl. D86—10)

Fig. 1.

Fig. 2.

Fig. 1 is an elevational view of a lipstick container, showing my new design; and

Fig. 2 is a top plan view, the opposite end being substantially similar thereto.

I claim:

The ornamental design for a lipstick container, substantially as shown and described.
